N. I. KAHAN

Des. 157,762

SCARF OR SIMILAR ARTICLE

Filed Feb. 2, 1949

NATHAN I. KAHAN,
INVENTOR.

BY Nicholas M. Welfand
ATTORNEY

UNITED STATES PATENT OFFICE

157,762

SCARF OR SIMILAR ARTICLE

Nathan I. Kahan, New York, N. Y.

Application February 2, 1949, Serial No. 629

Term of patent 3½ years

(Cl. D3—12)

To all whom it may concern:

Be it known that I, Nathan I. Kahan, a citizen of the United States of America, residing in New York city, county of New York, and State of New York, have invented a new, original and ornamental Design for a Scarf or Similar Article, of which the following is a specification, reference being had to the accompanying drawing, forming part thereof, wherein,

The figure on the drawing is a plan view of a scarf showing my new design.

I claim:

The ornamental design for a scarf or similar article, substantially as shown.

NATHAN I. KAHAN.
